GARMENT

Jack French White, London, England, assignor,
by mesne assignments, to Martin-White of
America, Inc., New York, N. Y., a corporation
of Delaware

Application October 28, 1936, Serial No. 108,059
In Great Britain September 29, 1936

6 Claims. (Cl. 2—67)

This invention relates to garments for personal wear of the kind adapted to fit closely to the figure or to give what may be described as a skin-tight fitting such as is desired at the present time with bathing costumes, with which articles of personal wear the invention is more particularly concerned.

Hitherto, in using even such fabrics as possess what is known as two-way stretch, including tricot or knitted fabrics, and fabrics in which are incorporated rubber threads or filaments and more particularly filaments of coagulated rubber latex provided with a helical wrapping of fibrous material such as cotton or artificial silk, the "cutting" of the material or otherwise the fashioning of the garment to conform with the figure has been necessary particularly where in consequence of public taste the garment is intended to mould itself to the figure without suppressing its essential characteristics with a view to enhancing the aesthetic appearance of the human shape.

Not only has it been necessary to resort to fashioning but in view of the relatively limited degree of stretch possessed by the fabrics which have hitherto been employed for the purposes in question, it has been necessary to produce such articles in a large number of sizes or fittings, which fact necessitates dealers purchasing garments in a relatively large number of sizes in the relative quantities which they estimate will be required and taking the risk that at the end of the season they will be left with an excess of garments of certain sizes which they may find it difficult to dispose of without loss.

The invention is based upon the observation that by the employment of a fabric the basic material of which possesses a restricted or even substantially no degree of elasticity but which by the provision at relatively widely spaced intervals of elastic threads or filaments extending at least in two directions, with for instance one set or group of spaced elastic threads or filaments arranged at right angles with the threads or filaments of the other group, and applied to the basic material under tension in such manner that when the tension on the elastic threads is released they operate to draw up the basic material and impart to it what may be described as a roughly honeycomb structure due to the basic material intervening between the elastic threads or filaments being caused to crinkle, pucker or bulge, the necessity for "cutting" the fabric or otherwise fashioning the garment to conform with the human figure is unnecessary and with, for instance, a garment adapted to cover the upper portion of

the figure of a woman as does a bathing suit, it is merely necessary to take a rectangular piece of such fabric without any close regard to the size of the person, fold it in half, secure together the two edges remote from the fold and secure together the fabric for a suitable distance along one of the sides adjacent to that formed by securing together the two first-mentioned edges for a convenient distance intermediate in the width of the side so as to provide a portion which will be engaged between the legs of the wearer, the article so formed being thus in effect a rectangular bag in one side of which there are apertures through which the legs will pass, the opposite side being open or provided with an aperture through which the head and shoulders will extend.

While, when employing such a fabric, some degree of shaping or fashioning can be resorted to as, for instance, the cutting of the material to form a garment which even when not on the person exhibits a "waist", such fashioning or shaping is in fact generally unnecessary and if adopted will not in any way be comparable with the fashioning or shaping which it is necessary to employ to ensure that the garment moulds itself to the differences in level presented by the figure and may be resorted to merely in consequence of the difficulty which members of the public may have in believing that an article not so formed will fit the figure closely.

The invention consists, broadly, in garments for personal wear of the kind adapted to fit closely to the figure and in particular bathing costumes and garments of the like character formed from a fabric the basic material of which possesses a restricted or even substantially no degree of elasticity but which by the provision at relatively widely spaced intervals of elastic threads or filaments extending at least in two directions with, for instance, one set or group of spaced elastic threads or filaments arranged at right angles with the threads or filaments of the other group, and applied to the basic material under tension in such manner that when the tension on the elastic threads is released they operate to draw up the basic material and impart to it what may be described as a roughly honeycomb structure due to the basic material intervening between the elastic threads or filaments being caused to crinkle, pucker or bulge by taking a piece or pieces of such fabric cut substantially without regard to the conformation of the human figure, and without any close regard to, or consideration of, the dimensions of the figure or "size", and securing together certain of the

edges of the piece or pieces of fabric at positions appropriate to provide a covering for a portion or portions of the body of the wearer of the garment.

The invention consists, more particularly, in 5 a bathing costume or a garment of like character formed of such material which, when lying flat and untensioned has substantially two parallel sides and an opening located between such sides enabling the garment to be drawn on and aper- 10 tures in the opposite side through which the legs may pass, with a closed portion between such ap- ertures.

The invention consists more particularly also 15 in a bathing costume or a garment of like character formed from a single piece of fabric of the character above defined substantially of rectangular form folded in half and with the edges opposite to the fold joined together substantially throughout the length of such edges, and con- 20 nected together through an appropriate distance at a position intermediate between the sides con- 25 stituted by the fold and the joined edges for a dis- tance sufficient to provide a portion which will be engaged between the legs of the wearer.

25 To the side of the garment opposite to that having a joined portion which will be engaged be- 30 tween the legs of the wearer, shoulder straps or the like or means adapted to be engaged by shoul- 35 der straps or the like or equivalent means for preventing accidental or undesired displacement of the garment may be provided.

Thus, to the side in question there may be se- 35 cured pieces of fabric of the like character to that employed in forming the body portion of the garment adapted to extend over the shoulders and 40 optionally to provide sleeves and normally short sleeves.

Where a garment, in accordance with the in- 40 vention, is furnished with sleeves or portions ex- 45 tending over the shoulders and such portions are formed of a fabric of similar character to that of which the main portion of the garment is formed, such sleeves or portions extending over the shoulder may be cut and otherwise made 50 without substantial regard to the conformation of the shoulders.

The basic material of the fabric employed, in 50 accordance with the invention, may be of widely varying character and may be of wool, cotton, 55 silk or artificial filaments or mixtures of any of these and it may be a loom-woven, loom-knitted or knitted fabric, and it may be of such character that it is porous or permeable or it may be fin- 60 ished with coating compositions rendering it im- 65 permeable to water, and in such case may re- 70 semble material of the character known as oiled silk, American cloth and the like.

Normally, but not necessarily, the elastic 60 threads or filaments are of the type comprising a 65 core in the form of coagulated rubber latex pro- 70 vided with a helical wrapping of filamentary ma- 75 terial and the threads in question may be secured to the basic material in any suitable manner as, for instance, by a substantially non-extensible filament which is passed through the material about the elastic thread and again through the material and so on in a substantially helical manner, one group of elastic threads or filaments being arranged to extend parallel with the warp 75 of the threads and the threads or filaments of the other group being arranged parallel with the weft threads, and the interval between the weft and the warp threads when the elastic threads are under tension may, for instance, be in the neighbourhood of 1 inch so that the finished fabric has,

as above indicated, what may be described as a more or less honeycomb structure and in certain cases resembles a "smocked" fabric.

The invention will be described further in de- 5 tail and by way of example with reference to the accompanying drawing in which:—

Figure 1 illustrates the fabric employed in ac- 10 cordance with the invention in its fully tensioned state,

Figure 2 illustrating the fabric when the ten- 10 sion is relaxed,

Figure 3 is a view on a larger scale illustrating the mode of connecting the elastic threads to the fabric,

Figure 4 illustrates a piece of the fabric adapted 15 to be formed into a bathing costume,

Figure 5 illustrates the bathing costume off the figure of a wearer,

Figure 6 is a view illustrating the bathing cos- 20 tume on the figure of a wearer.

As will be seen from Figure 1, a sheet of the basic material 1 which possesses a restricted or substantially no degree of elasticity is provided at 25 relatively widely spaced intervals with two sets of spaced elastic threads or filaments, namely, the group 2 and the group 3, the individual filaments of each of the groups being applied under tension to the basic material, the threads or filaments of one group crossing the threads or filaments of the other group at right angles, the threads or filaments each of which in the construction illus- 30 trated in Figure 3 is constituted by a core filament of coagulated rubber latex 4 provided with a helical wrapping of artificial silk 5 and is secured to the basic material by stitches 6.

When the tension on the threads is released 35 they contract causing the basic material to be drawn up so as to provide a roughly honeycomb structure due to the basic material intervening between the elastic threads or filaments being 40 caused to crinkle or form puckers or bulges as indicated by 7 in Figure 2.

The degree of contraction secured by the elastic threads in a particular instance is such as to 45 reduce the dimensions of the squares formed by the crossing of the threads 2 and 3 from 1 1/4" side to 1/2" side.

In making a bathing costume with the mate- 50 rial a piece thereof, of the form substantially as indicated in Figure 4, namely, a piece of rectan- 55 gular form is taken, the two edges 8 and 9 being hemmed and the two edges 10 and 11 brought to- 60 gether by folding the piece of material in two and stitching while in this position to form a join 12.

The hemmed portion 9 is further joined for a 55 convenient distance indicated by the reference 13, and a strip of material, for instance a tubular tricot fabric 14 is passed through eyes 15 which are secured at 16 by stitching and through the hemmed portion.

As will be seen the garment is substantially 60 formless in the sense that it has no suggestion that when donned by the wearer it will fit the figure, or neatly conform or mould itself to the difference in level presented by the human figure.

This result is, however, achieved as is illus- 65 trated in Figure 6, which shows that the basic material between the rectangles formed by the crossing of the elastic threads is distended or the 70 puckers or bulges in the basic material are opened out or reduced.

What I claim is:—

1. A fabric comprising a sheet of substantially non-elastic basic material, a series of elastic threads independently attached to the surface of 75

2,134,630

5 said basic material in substantially parallel lines, a second series of elastic threads independently attached to said surface but extending in substantially parallel lines in a direction substantially perpendicular to the direction of the first named series of elastic threads, all said elastic threads being attached in a stretched condition to said basic material whereby the basic material will assume when not under stress a puckered 10 formation.

10 2. The fabric as claimed in claim 1 in which the threads of each series are substantially spaced from each other and lie between separate definite areas of puckered surface.

15 3. A fabric comprising a sheet of basic material which is substantially non-elastic, a series of spaced elastic threads extending in one direction with respect to the sheet of basic material, and a second series of spaced elastic threads extending 20 in a direction at substantially right angles to the threads of the first series and crossing the threads of the first series with the threads of each such series secured while under tension to relatively widely spaced intervals to the surface 25 of said basic material and operating when the tension on the threads is released to draw up substantially equally in all directions the portions of the basic material located between them and thereby impart to the basic material a surface 30 structure of a puckered character.

35 4. A fabric comprising a sheet of substantially non-elastic basic material, a plurality of series of spaced elastic threads, the threads of any one series extending substantially parallel to each other but the threads of different series extending in different directions, each thread of each series being independently and non-slidably attached to a surface of the basic material, the linear measure of that portion of the basic mate-

rial to which the elastic threads are directly attached being greater in the direction in which the threads of a series extend than the normal length of the elastic threads in that series but not greater than the length of said last named elastic 5 threads when extended to their elastic limit.

5. A fabric comprising a sheet of substantially non-elastic basic material, two groups of substantially parallel elastic threads, each thread of each group being independently attached to a surface 10 of said basic material substantially throughout the length of the thread; the threads of one group extending in a direction at a substantial angle with the threads of the other group and each elastic thread subtending a line of the surface 15 longer than the untensioned length of the thread, whereby the basic material is drawn up to form areas of puckered surface bounded by sections of said elastic threads and is capable of extension in all directions.

20 6. A garment for personal wear, the body of which is a strip of substantially non-elastic material, a series of spaced elastic continuous threads extending in one direction, and a second series of spaced elastic continuous threads extending in a 25 direction substantially at right angles to the threads of said first series, each thread of both series being independently and non-slidably attached to a surface of said basic material, the construction and arrangement being such that 30 when the threads are not under tension the portions of the basic material located between them are drawn up substantially equally in all directions and a surface structure of puckered character is imparted to the basic material, having 35 two non-adjacent edges of the strip secured together and means for securing the middle portion of the edges of one end of the body.

JACK FRENCH WHITE.
